UNITED STATES PATENT OFFICE.

CLEMENT CLEVELAND, OF NEW YORK, N. Y.

HAT-PIN.

1,118,473.

Specification of Letters Patent. Patented Nov. 24, 1914.

Application filed April 19, 1913. Serial No. 762,181.

To all whom it may concern:

Be it known that I, CLEMENT CLEVELAND, a citizen of the United States, residing in New York city, in the county of New York and State of New York, have invented certain new and useful Improvements in Hat-Pins, of which the following is a specification.

This invention relates to combinable hat-pins, and a principal object of the invention is to provide a composite or duplex hat-pin adapted for use in a single pin, or as a pair of separate pins, and also as a safety device.

In the accompanying drawing forming a part of this specification, Figure 1 is a side view,—partially in section, of a safety hat-pin made in accordance with my present invention and having the two component pins assembled as when in use as a combined or duplex pin. Fig. 2 is a similar view illustrating the manner of assembling the two combinable pins preparatory to inserting them into a hat.

Similar characters designate like parts in both of the figures.

As shown in the drawing, the duplex hat-pin comprises the outer tubular pin, designated in a general way by B, and having the entering-point, 2, at one end, and some suitable head, as h, at the other end; this view also shows the pin B assembled with a central pin C for use as a combined and safety hat-pin. Fig. 2 shows the tubular pin B with a second pin, C, located centrally therein, after being inserted from the left-hand in Fig. 1, through the entrance 3; this central pin has a head d, and the point 4 extending beyond the point-end 2, so these two entering-ends, 2 and 4 together constitute one extended entering-point 2—4, for the combined pins B and C. When the two pins are thus assembled, they constitute one article, one pin, which is adapted to be used in all respects as an ordinary single hat-pin. When thus used, however, on being inserted into a hat, the central pin C may be withdrawn and used as an ordinary hat-pin, separately and in another location, so the then unassembled pins are each operative independently of the other.

Fig. 1 also shows a hat outline, N, with the pin B in position, as if it had been inserted in the manner above described, but with the pin C,—after its withdrawal as above stated,—reinserted from the opposite direction, so the head d forms a safety guard

for the point 2 of the tubular pin B, while the point 4 of the central-pin C is guarded within the bore 6 of the pin B, thus forming a safety device of each pin for the point of the other, while the head h has a part thereof forming an end-stop for the point 4 of said central pin.

When the two pins are assembled in a manner indicated in Fig. 2, they become practically a single pin and may then be inserted through the hat, as N, Fig. 1, after which the central pin may be withdrawn and re-inserted from the point end of the pin B, as shown in Fig. 1, so that when thus combined each of the two pins has a head, and when thus reversely combined, have a head at each end thereof. The tubular pin B is shown provided with an entrance, as 3, near the head-end thereof for an insertible central pin, and has this entrance-way branching from one side of the tube, for thereby forming in the tube a reserved portion serving as a point-receptacle with a closed end for receiving the point of the central pin when this is inserted from the point-end of the tubular pin.

As one convenient arrangement for meeting the ordinary requirements, the branch-way entrance may, as indicated in Figs. 1 and 2, consist of a narrow slot, 3, formed in one side of the tubular pin B and extending to within a short distance of the head h. When this arrangement is used and on account of the considerable difference in the external diameters of the two pins, it is evident the slot 3 may be only wide enough to allow the entrance of the small pin C, especially as this central pin will usually have a considerable degree of flexibility. In practice the branch-way entrance may be obtained and arranged in varying specific ways, while securing the required result in substantially the same manner.

The tube of the pin B, may in practice be made extremely thin, preferably of hard-drawn, or tempered metal; usually a steel tube suitably tempered will be preferable. But to facilitate their illustration I have shown the diameters of both pins somewhat enlarged and also of a relatively reduced length.

Having thus described my invention, I claim:

1. In a duplex hat-pin, a tubular pin having a branch-way entrance for an insertible central pin, and having this entrance-way

branching from one side of the tube at a point near but not at the head-end of the tube of the tubular pin, and having the bore of the tube constituting a point receptacle provided with a point-stop for receiving and stopping the point of the central pin when this is inserted from the point-end of the tubular-pin.

2. In a duplex hat-pin, a tubular pin having at the head-end thereof a branch-way entrance for an insertible central pin, and having this branch-way located divergent from the bore of the tube, a point-receptacle consisting of a part of the tube between the head-end of the tube and said branch-way entrance for receiving the point of the central pin when this is inserted from the point-end of the tubular-pin, and a stop closing the head-end of the point-receptacle.

3. In a duplex hat-pin, a tubular pin having at the head-end thereof a branch-way entrance for an insertible central pin, a point-receptacle consisting of a part of the tube between the head-end of the tube and

said branch-way entrance for receiving the point of the central pin when this is inserted from the point-end of the tubular-pin, a head on the insertible pin arranged for constituting a stop when this pin is inserted through said branch-way entrance. 25
30

4. In a duplex hat-pin, a tubular pin having at the head-end thereof a branch-way entrance for an insertible central pin, a point-receptacle consisting of a part of the tube between the head-end of the tube and said branch-way entrance for receiving the point of the central pin when this is inserted from the point-end of the tubular-pin, a head on the tubular pin and arranged for closing the head-end of the point-receptacle, 35
40 and a head on the insertible pin arranged for constituting a stop when this pin is inserted through said branch-way entrance.

CLEMENT CLEVELAND.
